PROPELLING PENCIL

Alfred Dillier, Aesch/Basel, and Joseph Gabler,
Basel, SwitzerlandApplication December 9, 1932, Serial No. 646,526
In Germany December 14, 1931

3 Claims. (Cl. 120—18)

The present invention relates to a mechanical pencil with a lead holding sleeve containing the lead and surrounded by a threaded sleeve and an adjusting pin sliding in the lead holding sleeve with a toothed cheek engaging in the thread of the threaded sleeve through a guide slot of the lead holding sleeve, and by means of which on the use of longer leads a separate holding of the lead and more simple feed thereof is attained

5 than with known mechanical pencils.

10 This is attained with the pencil, according to the invention, by the lower end of the lead holding sleeve being slotted and carrying on its circumference conical pressing segments on to 15 which is pressed the threaded sleeve by the action of a pressure spring supported in the pencil sleeve so that the lead is clamped at this point and on the displacement of the threaded sleeve against this spring by pressure on the head of 20 the pencil, is released.

Several embodiments of the invention are shown in the drawing, in which

Fig. 1 is a longitudinal section of the pencil,

25 Fig. 2 is a partial longitudinal section on a larger scale,

Fig. 3 is a cross-section on the line III—III of Fig. 1,

30 Figs. 4 and 5 show a cross-section on the line V—V of Fig. 1 in different positions,

Fig. 6 shows a further cross-section on the line 35 VI—VI of Fig. 1,

Fig. 7 is a partial longitudinal section of a second form of construction.

Fig. 8 is a further partial longitudinal section 40 on a plane displaced by 90° to that according to Fig. 7.

Fig. 9 shows a cross-section of this on the line IX—IX of Fig. 7, and

Fig. 10 is a cross-section on the line X—X.

45 In Fig. 1, 1 is the pencil case, which has at the front end a conical tip 2 provided with three longitudinal slits 2a, and which is screwed into the pencil case 1 by means of a threaded projection. The tip 2 guides the lead M at the front

45 end. At the rear end of the case 1 is inserted a plug 3 on which is screwed a cap 4. On the cap 4 is placed a top 5 movable longitudinally and also revolvably and in which is fixed an adjusting pin 6.

50 The adjusting pin 6 passes through the plug 3 and projects into the lead holding tube 7 the upper end of which is swivelly mounted in said plug. At the lower inward V-shaped end, the adjusting pin 6 has a transverse slot in which fits

5 a guide piece 8a which operates in the tube 7. The key 8 is arranged to bear on the upper end of the lead holding tube 7. In the lead holding tube 7 is placed above the lead M the pushing pin 9. On the upper end of pin 9 is fixed the toothed cheek 10, the teeth of which project through a longitudinal slot 7a of the lead holding tube 7, and into the thread of the threaded sleeve 11 also provided with a longitudinal slot 11a, by which the threads of tube 11 are interrupted. 10 The lead holding tube 7 is provided opposite the slot 7a with a second short slot 7b through which the key 8 also extends, as shown. The threaded sleeve 11 surrounds by its lower end part of the bottom end of the tube 7 constructed as a triple 15 slotted pincer, and which by means of conical pressing segments 12 with which it is provided is pressed inwardly radially on to the lead and holds this fast. In the centre of the case 1 is fixed a bush 13 and between this and a ring 14 20 fixed on the threaded sleeve 11 is a pressure spring 15 which forces the threaded sleeve 11 upwardly and thus effects the holding of the lead in the lead containing sleeve 7 and prevents the intermediate tube 11 from turning.

25 When, by pressing down the head 5, the pincers 12 of the lead holding sleeve 7 pressed round the lead are released and the head 5 is then manually rotated until the toothed cheek 10 comes into the slot 11a of the threaded sleeve 11, the 30 loosened lead M can be moved by hand as desired.

To adjust the lead from time to time as required, when writing, the head 5 is depressed and turned manually, so that the adjusting pin 6 35 by means of the key 8 which it carries pushes the intermediate tube 11 downwardly, to release the lead, and also causes the lead receiving tube 7 to be turned, and therefore the toothed cheek 10 of the pushing pin 9 by its engagement with the internal thread of the non-rotating intermediate tube 11 causes said pushing pin to move longitudinally, and to correspondingly move the lead M, as will be understood.

40 When a lead is used up, it is necessary with existing systems to screw back the whole guide mechanism in order to insert a fresh lead, which is made unnecessary by the present construction. The slot 11a in the threaded tube 11 permits the immediate sliding back of the fresh long lead into 45 the writing position.

The lead cannot slide back, contrary to the case with known pencil case constructions.

50 The example according to Figs. 7—10 has for its object a simplification of the adjustment of

55

the lead by hand. The pencil in itself is made the same as for the first example. There is, furthermore, fixed at the upper end of the threaded sleeve 11 a steeply bevelled bush 17 and a 5 roller 18 projecting laterally on the key 8, which roller lies exactly above the upper edge of the bush 17. At the lowest point of the top edge of the bush 17, there is a lateral projection 19 which carries a cam 20 with two inclined sides. 10 The highest point of the top edge of the bush 17 coincides exactly with the longitudinal slot 11a of the threaded sleeve 11. If now the head 5 of the pencil is pressed down, the roller 18, having been by very slightly turning the head removed 15 from dead center position, presses down on the inclined camming upper edge of the bush 17 which, consequently, rotates together with the threaded sleeve 11 until the roller 18 has reached the lowest point of the bush 17; in this position, 20 the toothed cheek 10 projects into the slot 11a of the threaded sleeve and the lead can be moved as desired. On releasing the head 5, the roller 18 strikes on the tip of the cam 20 and runs down on one of the faces, so that the bush 17 together 25 with the threaded sleeve 11 is rotated by an angle sufficient to again bring the toothed cheek 10 out of the range of the slot 11a.

To insert a fresh lead, it is sufficient with this form of construction to screw off the head and 30 take out the adjusting pin 9, without taking the pencil apart and then having to screw it all together again.

Our improved mechanical pencil has the following advantages:

35 It permits the use of longer leads which is of advantage particularly in drawing. In addition, the lead can be instantaneously held fast by spring pressure so that in writing and drawing no pressing back on the lead takes place. No 40 breakage of lead can take place by this lead being too firmly gripped. As no two-part guide cone is used as with previous constructions, no lateral displacement of the lead can take place in drawing in consequence of want of accuracy 45 of the cone. The jaws which hold the lead fast have movement only in a lateral direction, and they are entirely invisible to the eye.

What we wish to secure by U. S. Letters Patent is:—

50 1. A mechanical pencil comprising a casing tube 1 having a conical tip 2a at one end, a head 5 slidably and revolvably mounted on the other end of the casing tube, an adjusting pin 6 secured to and movable with said head and having 55 a radially projecting key 8 at its inner end; a lead-receiving tube 7 fixed against longitudinal movement and revolvable in the casing tube and in the inner end of which said adjusting pin is

movable, said lead-receiving tube having radially movable lead gripping members at its outer end provided on their outer sides with cams 12, an intermediate tube 11 through which the lead-receiving tube extends and which intermediate tube is revolvable and is longitudinally movable on said lead receiving tube, said intermediate tube having means at its outer end to coact with said cams to release said members of the lead-receiving tube from the lead when said intermediate tube is moved outwardly by said key, a spring to resist outward movement of the intermediate tube; said intermediate tube having internal screw threads and being provided on one side with a longitudinal slot interrupting its 10 screw threads, and said lead-receiving tube having a longitudinal slot in one side through which said key extends, and a pushing pin 9 slideable in the inner portion of the lead-receiving tube and provided at its inner end with a toothed cheek 10 projecting radially therefrom and through said slot of said lead-receiving tube, said toothed cheek permitting longitudinal movement of said pushing pin by said adjusting pin when said cheek is in registry with said slot of said intermediate tube, and the teeth of said cheek being engagable and coactive with the internal threads of said intermediate tube to cause lead adjusting longitudinal movement of said pushing pin when the toothed cheek of the latter is engaged 20 with the thread of the intermediate tube, and said adjusting pin and hence also said lead receiving tube is turned by means of said head. 25

2. A mechanical pencil comprising a casing tube, a lead-receiving tube fixed against longitudinal movement and revolvable therein, a longitudinally movable, non-revolvable internally screw threaded intermediate tube through which said lead-receiving tube extends, a spring to resist movement of the intermediate tube in one 30 direction, said lead-receiving tube and said intermediate tube having means to cause the former to grip the lead while the intermediate tube is in normal position and to release the lead when the intermediate tube is moved against the 35 resistance of the spring, a pushing pin in the lead-receiving tube having means to engage the screw thread of the intermediate tube and thereby cause said pin to move axially when the lead receiving tube is revolved and means to operate 40 the intermediate tube and the pushing pin. 45

3. A pencil as claimed in claim 2, including means to at will axially move the pushing pin or to engage the same with the thread of the intermediate tube and thereby revolve the lead receiving tube. 50 55
